UNITED STATES PATENT OFFICE.

EDWIN REUEL MERRILL, OF COLUMBUS, OHIO, ASSIGNEE, BY MESNE ASSIGNMENTS,
TO THE JEFFREY MANUFACTURING COMPANY, A CORPORATION OF OHIO.

MINING-MACHINE.

1,073,271.

Specification of Letters Patent. Patented Sept. 16, 1913.

Application filed November 30, 1897. Serial No. 660,267.

To all whom it may concern:

Be it known that I, EDWIN REUEL MERRILL, a citizen of the United States, residing at Columbus, in the county of Franklin and State of Ohio, have invented certain new and useful Improvements in Mining-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The principal object of the invention is to provide in a long-wall mining machine of the class shown and described improved mechanism for adjusting the cutter mechanism with respect to the frame angularly about a transverse axis.

Other objects will be apparent from the following specification and claims.

Of the drawings Figure 1 is a plan view 25 of a mining machine embodying my improvements. Fig. 2 is a side elevation thereof. Fig. 3 is an elevation of the opposite side of the machine from that shown in Fig. 2. Fig. 4 is an end elevation. Fig. 30 5 is a transverse vertical section through the cutter-actuating devices, on a slightly reduced scale. Figs. 6 to 14 are detail views of the cutter wheel.

In the drawings, A, A', designate the 35 longitudinal side bars of the main frame, which may be formed of angle iron, or any other suitable material, and are connected at their forward ends by a cross bar, A². The main frame thus formed is adapted to support and carry a cutter-wheel, C, a motor, D, and gearing for driving the cutter wheel from the motor; and in order that the cutter may move longitudinally along the face of the coal, said frame is provided with 45 suitable guiding and supporting wheels.

In the embodiment of my invention, here- 50 in illustrated, two guiding and supporting wheels, E, E', are provided, they being arranged in the same longitudinal line at one side of the center, transversely, of the said frame, and arranged to travel upon a single guide rail, F', which is arranged upon the floor of the room in which the machine is operated. Preferably these wheels, E, E', are arranged as shown in Figs. 1 and 2, that

at E being situated near the forward end of the machine, and mounted on a suitable axle journaled in the main frame, and the other wheel, E', being mounted between ears or lugs, e, projecting rearwardly from the rear wall of a casing, F, mounted upon and connecting the rear ends of the aforesaid side bars, A, A'.

The cutter wheel, C, is carried by a laterally projecting arm, or plate, C', which 65 at its inner end is rigidly secured to or formed integral with a sleeve, G, which is secured to the side of the casing, F, and provided with a portion which extends inwardly, transversely of the machine, as 70 shown particularly in Fig. 5. As shown, this sleeve, G, is provided at its outer end, with an enlarged portion, G', which serves as a casing for a portion of the gearing by which the cutter wheel is rotated, and which 75 will be hereinafter more particularly described. The forward enlarged portion, G', is not cylindrical, and is provided at its lower edge with a horizontal laterally and forwardly projecting flange, g, which is rigidly bolted to the plate C'.

The cutter wheel, C, is formed of a ring like plate c provided with a series of gear teeth, c', upon its upper face, and with a series of peripheral sockets in which are fitted 85 the cutter bits, C², said bits being held rigidly in their respective sockets by means of set screws, c². This ring like plate, c, is provided with a central hub, c³, which is fitted about a stud, H, rigidly secured to and 90 depending from the plate C'; and the cutter wheel is supported vertically by means of a bottom guard plate, C⁴, which is connected to the plate or arm, C', by means of bolts, c⁴.

With the gear teeth, c', meshes a gear, H', which is secured to a shaft, H², journaled or mounted in the aforesaid sleeve, G, and provided at its inner end with a driving bevel, H³, a suitable aperture being formed 100 in the lower wall of the enlarged portion, G', of said sleeve, to permit the teeth of the wheel, H', to engage with those at, c'.

Power is transmitted from the motor, D, to the bevel wheel H³, and, by the devices 105 last described, to the cutter wheel as follows:

D' designates a pinion secured upon the armature shaft of the motor, and said pinion meshes with a gear, D², mounted on a 110

shaft journaled in a suitable bearing supported on the main frame; and provided at its rear end with a bevel pinion, D^3 , which meshes with the aforesaid bevel gear, H^3 .

5 The motor D is provided with suitable current controlling devices d , arranged as shown.

As it is frequently necessary that the angle of the cutter wheel, C, to the floor upon 10 which the machine is resting should be varied, in order, for example, that the said wheel may be properly guided about any mass of material which may be in its path and of such nature as not to be cut by the 15 cutters, I have provided the following described devices for readily adjusting said wheel to any desired angle.

The sleeve, G, G', is provided with forwardly and rearwardly projecting lugs, i , i' , 20 each having formed therein a guide slot, i^2 , extending concentric with the axis of the shaft H^2 . Through these guide slots, i^2 , extend the bolts, i^3 , by which the sleeve, G, G', and the cutter wheel are secured to the 25 casing, F. The forwardly projecting ear or flange, i , is connected with one end of a lever, K, which is fulcrumed at, k , upon the side of the motor, D, and has at its forward end a toothed segment, k^2 , extending concentric with the pivot, k , and to points above 30 and below the lever arm. With the teeth on the segment, k^2 , engages a pinion, L, mounted on a shaft, L', which is journaled in bearings on the side bars, A, A', and provided with a worm wheel, L². By turning the said wheel, L², it will be seen that the forward end of the lever, K, will be raised or lowered as desired, and thereby the cutter wheel, and its supporting parts will be 35 rocked vertically in vertical longitudinal planes, the guide slots, i^2 ; being of such length as to permit this movement. Preferably the rear end of the lever, K, is expanded to form the loop-like terminal, k^3 , and within 40 this part, k^3 , are mounted coiled springs, k^4 , the inner adjacent ends of which bear upon opposite sides of the bolt, k^5 , by which the lever, K, and ear or lug, i , are connected.

To move the machine longitudinally of its 50 supporting track along the face of the coal, I preferably employ a rope or cable, M. One end of the cable or rope is provided with an eye or loop, m, adapted to engage with a hook, a, secured to the side bar, A', at its 55 forward end. From such hook, a, the cable extends around a pulley, O, which is connected with a post or upright, O', held rigidly by any suitable means at the desired distance in advance of the machine when 60 beginning its cut, and the other end of the cable is connected with a winding drum, P, mounted upon the forward portion of the main frame. This drum, P, is positively driven by the following devices. On the 65 shaft, H^2 , between the bevel wheel, H^3 , and

the inner end of the sleeve, G, is secured a pinion, Q, which meshes with a gear wheel, Q', mounted on a shaft, Q², extending parallel to the shaft, H^2 . This shaft carries on the outer side of the machine an eccentric, 70 Q³. This reciprocates a slide rod, R, in a guide at, r , being joined thereto by a connecting rod, r' . The slide rod is at the other end joined to a connecting rod or pitman, R', which is pivoted to a pawl carrier, R². 75 S is a ratchet wheel on a shaft at s extending transversely of the machine at its forward end.

r^2 is the pawl supported on the carrier, R², the latter being hinged at the axis of 80 the ratchet wheel, S. The shaft, s, carries a pinion, S', which drives the winding drum, P, through the gear wheel, T', the drum being mounted on a shaft parallel to that at s. The ratchet wheel, S, is provided with relatively small teeth, small enough to insure sufficient strength at all times, and so as to provide for a variation in the speed of the advance of the machine.

T² is a bar held in the line of the pawl, r^2 , 85 and adapted to be adjusted to one position or another, and to be fastened by a clamping screw, t. The bar, T², can be moved forward far enough to allow the pawl to engage with the fourth tooth (for instance, 95 backward from its rearmost position) and at such time the rope will have greater lengths taken up at each stroke of the eccentric, Q³. Or the bar, T², can be so adjusted that the pawl, r^2 , shall engage with 100 the third tooth back, or the second, or the first, in each such instance the distance of advance of the carrier will be relatively shorter at each stroke of the eccentric. Or the adjusting bar, T², can be pushed rearward so far as to hold the pawl out of engagement entirely with the wheel, and stop 105 the advance of the carrier even when the motor is in action.

The parts of the above machine, it will 110 be seen, are arranged so as to insure the covering of short dimensions in all directions in which space is limited in mines worked on the "long wall" plan. That is to say, the present machine is exceedingly low 115 and narrow. In operating it, after it has been once set in position and the feeding cable has been engaged with a properly supported stationary wheel or guide in advance of the machine, it is, practically, 120 merely necessary for one of the operators to accompany the machine at the front end to see that the cutting wheel is revolving in the right planes, and to adjust it, if necessary, by means of the worm wheel, L², and the lever, K, and for an assisting operator to 125 follow the machine for the purpose of picking up each successive section of the track, F, and advancing the latter past the machine (over or by the outer side of it) to the 130

one in front who places it in proper position to receive the carriage wheels when they reach it.

I am aware of the fact that the adjustment of the cutter wheel, broadly considered, has been heretofore proposed. But the results of practical use of such a machine has led me to devise the means herein presented for applying a powerful leverage to the carrier of the cutter wheel when it is desired to compel it to alter its path; the devices for this purpose having consisted of a short lever plate with a rack and pinion in or nearly in the transverse, vertical, planes of the cutter, and requiring that the operator should have access to the outer side of the machine in such transverse planes of the wheel. This is generally very difficult in the mines where such machines are used, because of the "posting", and the piling of the refuse up to a vertical plane close to the coal face. With the present machine the operator can make all such adjustments from the front end, and at a distance from the cutter wheel.

The arrangement of the motor herein shown assists in attaining these ends, that is providing long leverage for the adjusting of the cutter wheel and powerful devices, near the front end of the machine, and at a distance from the center.

The worm wheel L^2 is actuated by a worm, L^3 , mounted on a shaft, L^4 , supported in suitable bearings, L^5 , L^6 , and having at its forward end a hand wheel, L^7 . By turning the latter it will be seen that motion is transmitted to the wheel L^2 , and that the cutter-wheel can be adjusted with these devices. The worm and worm wheel form a lock for holding the wheel in its proper position after adjustment. But to supplement this locking action I employ a clamp for the shaft L^4 . This clamp can be provided by forming one of the bearings, as that at L^6 , in two parts, and providing them with a screw or bolt, O^5 , whereby they can be tightly drawn together and grip the shaft to prevent its slipping from the locked position.

It will be seen that in the present machine the cutter-wheel which is adjustable around a horizontal axis can be regarded as being supplied with a lever which is rigid with it. To this lever is pivoted the vibrating lever, K , and the latter can be arranged in such manner as to consume but little space. The motor is arranged in front of the cutter driving gearing, the adjusting devices for the wheel carrier are in front of the motor, the carriage advancing devices are in front of the wheel adjusting devices. This arrangement brings the several devices within easy access and the manual devices for controlling the motor, adjusting the cutter wheel carrier, and varying the rate of feed,

respectively, are grouped at the front end of the machine where they can readily be reached by the operator.

The track wheels and the track, I arrange relatively nearer the inner side line of the carriage, so that the outer portion of the carriage will serve to counterbalance the cutter-wheel, both of which are adapted to vibrate or rock bodily around the supporting wheels on the track.

By reference to Figs. 5 and 14, it will be seen that the stud, H , about which the cutter-wheel, C , revolves, is provided with a central oil chamber or receptacle, h , from which lead a series of distributing ducts, h' . Two concentric spacing rings, c^5 , c^6 , are also interposed within the hub, c^3 , between the plates C' , C^4 .

In addition to the support above described for the cutter wheel, namely, that afforded by the plates, C' , C^4 , and the bolts, c^4 , connecting the same, one or more depending lugs c^7 , may be provided on the plate, C' , the projecting portions of said lugs extending beneath a flange or ring, c^8 , which is fastened to the body part of the wheel, C , as shown in Figs. 5 and 14.

What I claim is:—

1. In a side cut or long wall mining machine, the combination of a carriage, a cutter wheel projecting laterally from the carriage, a carrier for the wheel adjustable relatively to the carriage on a transverse horizontal axis, and a train of devices for adjusting said carrier, the said train having a flexible spring controlled connection between two elements thereof through which power for operating the carrier is applied, substantially as set forth.

2. In a side cut or long wall mining machine, the combination of a carriage, a cutter wheel projecting laterally from the carriage, a carrier for the wheel adjustable relatively to the carriage about a transverse horizontal axis, a lever rigidly connected to the wheel carrier, a supplemental lever flexibly connected to the rigid lever for adjusting the wheel carrier, and means for controlling said supplemental lever, substantially as set forth.

3. In a side cut or long wall mining machine, the combination of a carriage, a wheel projecting laterally from the carriage, a carrier for the wheel adjustable around a transverse horizontal axis, a lever flexibly connected to the wheel carrier, and power devices accessible at the front end of the machine for operating said lever and adjusting the wheel carrier, substantially as set forth.

4. In a side cut or long wall mining machine, the combination of a carriage, a cutter wheel projecting laterally from the carriage, a wheel carrier adjustable around a horizontal axis, a lever flexibly connected to the

wheel carrier, a rack and pinion connected to said lever for operating it, and means for operating said rack and pinion, substantially as set forth.

5. In a side cut or long wall mining machine, the combination of a carriage, a cutter wheel projecting laterally from the carriage, a cutter wheel carrier adjustable around a horizontal axis, an electric motor on the carriage in front of the cutter wheel, a lever connected to the cutter wheel carrier and mounted at points adjacent to the motor, supports for said machine arranged on a longitudinal line between the longitudinal median lines of the motor and of the cutter wheel, and means in front of the motor comprising a worm for actuating said lever to adjust the cutter wheel carrier, substantially as set forth.

20. 6. In a side cut or long wall mining machine, the combination of a carriage, a cutter wheel projecting laterally from the carriage, an adjustable cutter wheel carrier having a sleeve G, a motor in front of the cutter wheel, adjusting devices for the cutter wheel carrier in front of the motor, supports for said machine arranged on a longitudinal line between the longitudinal median lines of the motor and of the cutter wheel, and carriage moving devices in front of the said cutter wheel carrier adjusting devices, substantially as set forth.

7. In a machine of the class described, the combination with a cutter wheel, and a supporting arm or plate C', of a tubular hub H having its upper end fitted in an aperture in said plate, a relatively small plate C⁴ engaging with the lower end of said hub and rigidly secured to the plate C', two concentric spacing rings c⁵ and c⁶ arranged about the hub between said plates C' and C⁴, a cutter wheel having a ring-like body which extends between said plates and is fitted to said ring c⁶ and provided with a series of peripheral sockets and with an annular recess in its upper surface, a ring c⁸ seated in said recess, secured to the cutter wheel and extending inwardly beyond the said recess in its upper surface, and a lug c⁷ depending from the plate C' and adapted to engage with the under side of the said ring c⁸, substantially as set forth.

8. In a mining machine, a lateral cutter wheel having a horizontal axis of adjust-

ment combined with a train of devices for 55 adjusting the wheel around said axis, the said train having a flexible spring controlled connection between two elements thereof through which power for adjusting the carrier is applied, substantially as set forth.

60

9. In a mining machine, the combination of a carriage, a laterally projecting cutter wheel, a carrier for the cutter wheel adapted to turn about a horizontal axis transverse of the carriage, and a train of devices for adjusting said carrier, the said train having a spring interposed between two of the elements thereof, whereby the said carrier is yieldingly controlled, substantially as set forth.

70

10. The combination of a frame or bed, means for supporting and guiding the bed along the ground, a laterally projecting cutter wheel, an adjustable carrier for said cutter wheel, an adjusting lever connected to 75 said cutter wheel carrier, a power applying device connected to said lever for actuating it, and means supplemental to the lever and to its adjusting devices for fastening the said cutter wheel carrier in either of several 80 positions of adjustment.

11. In a machine of the class described, the combination of a main frame, means for supporting and guiding the frame, a laterally projecting cutter wheel, an adjustable 85 cutter carrier, fastening devices for securing said cutter wheel carrier in either of several positions of adjustment, an adjusting lever independent of said fastening devices and connected to the said cutter wheel carrier, 90 and means for actuating and locking said lever in either of several positions.

12. In a long wall mining machine, the combination with a carriage, a cutter wheel projecting laterally from the carriage and a 95 cutter wheel carrier adjustable about a horizontal axis transverse of the carriage, of a lever, a yielding connecting device interposed between said lever and said cutter wheel carrier, and means for actuating said 100 lever.

In testimony whereof, I affix my signature, in presence of two witnesses.

EDWIN REUEL MERRILL.
